UNITED STATES PATENT OFFICE

2,673,389

BUFFING WHEEL CONSTRUCTION

Paul E. Hawkinson, Minneapolis, Minn., assignor
to Paul E. Hawkinson Company, Minneapolis,
Minn., a corporation of Minnesota

Application May 5, 1952, Serial No. 286,083

2 Claims. (Cl. 29—79)

1

My invention relates broadly to abrading wheels, and more specifically to wheels for buffing the rubber treads on pneumatic tires. More specifically, my invention relates to buffing wheels for truing up the shoulder portions of pneumatic tires incidental to and prior to the application of new tread material to the buffed peripheral surface.

The primary object of my invention is the provision of a device of the class described, which is inexpensive to produce, which is effective in its cutting action, and in which the abrading surface may be renewed or replaced with a minimum of time, effort and expense.

A still further object of my invention is the provision of a device of the class described, in which the peripheral buffing surface is made up of a plurality of inexpensive sheet metal abrading bands which may be readily installed and replaced upon the buffing head, which are extremely inexpensive to produce, light in weight and inexpensive to ship.

A still further object of my invention is the provision of a device of the class described, which provides a maximum of safety to the operator.

The above and still further objects of my invention will become apparent from the following detailed specification, appended claims, and attached drawings.

Referring to the drawings, which illustrate the invention, and in which like characters indicate like parts throughout the several views:

Fig. 1 is a side elevation of my novel device, some parts being broken away.

Fig. 2 is a view partly in top plan and partly in section, illustrating my device in use upon the shoulder of a pneumatic tire.

Fig. 3 is a view in perspective of the sheet metal buffing bands utilized in my structure.

Referring with greater particularity to the drawings, the numeral 1 indicates a mounting head preferably, and as shown, being provided with a central mounting aperture 2. Head 1 also has a circular outer peripheral surface 3, laterally-spaced side surfaces 4, and opposed outwardly-opening anchoring channels 5 inwardly spaced from said outer peripheral surface 3. Channels 5 are circular. The shape of the mounting head 1 radially outwardly of the channels 5 may vary from the generally tapered one shown, to a perfectly round one. In any event, this shape must necessarily approximate closely that of the buffing bands to be utilized thereon.

For this purpose, I provide sheet or buffing bands 6, shown as being formed in generally U-shaped design from resilient sheet metal stock, 55

2

and stamped or perforated to provide a plurality of closely-spaced barbs 7 of the type generally described in detail in my Patent 2,240,559.

As shown, the legs 8 of the band 6 are provided with depressed portions defining inwardly-extended transverse ribs 9 and outwardly-opening transverse channels 10.

As above indicated, the shape of the buffing bands 6 conforms generally to the cross-sectional shape of the radially outer portion of the buffing head, including the channels 5 and the circular peripheral edge 3. With such an arrangement it should be obvious that as the resilient buffing bands 6 are pushed radially over the peripheral edge of the mounting head 1, to the position shown in section in Fig. 2, said buffing bands 6 will snap into position with sufficient force to retain themselves locked within the channels 5, while the other resilient clips 6 are put in place on said head 1 and while clamping plates 11, one on each side of said head 1, are placed in position. It will be noted that the head 1 is provided with a plurality of circumferentially-spaced transverse openings 12 therethrough. Likewise, the clamping plates 11 are provided with central openings 13, which are alignable with the opposite ends of the opening 2 in the head 1, and also with circumferentially-spaced openings 14, which are alignable with the openings 12 in the head 1. Nut-equipped clamping bolts 15 retain the clamping plates 11 in snug engagement on opposite sides of the mounting head 1, and cause the laterally inwardly-projecting annular beads 16 to exert clamping pressure upon the opposite end portions of the buffing band 6 within the channels 10 thereof. Preferably, and as shown, beads 16 are provided with relatively sharp edges 17 so as to insure greater clamping pressure upon the buffing bands 6 therebetween and the bottom of the channels 5 in the mounting head 1.

While I have shown in the drawings, and herein described a preferred embodiment of my invention, it should be obvious that the same is capable of modification without departing from the spirit and scope of the invention, as defined in the appended claims.

What I claim is:

1. A buffing wheel comprising a mounting head having a circular outer peripheral surface and laterally-spaced side surfaces defining opposed outwardly-opening circular anchoring channels inwardly spaced from said outer peripheral surface, a circumferentially-extended series of generally U-shaped sheet metal abrading bands applied over the periphery of the mounting head in radially inwardly-extended relation thereto

and having transversely-extended depressed portions defining inwardly-extended ribs and outwardly-opening channels, the said ribs of the opposite legs of said U-shaped sheet metal bands being seated in the circular channels of the mounting head, opposed clamping plates disposed adjacent opposite side surfaces of the mounting head and having inwardly-extending annular beads seated in the channels of the U-shaped bands, and means for securing the clamping plates to the head and maintaining the said beads thereof under clamping pressure against said bands.

2. The structure defined in claim 1, in which said abrading bands are resilient and snap into 15

position on said mounting head with sufficient force to retain themselves in position prior to clamping pressure exerted thereon by the clamping plates.

5

PAUL E. HAWKINSON.
